UNITED STATES PATENT OFFICE

147,961

DESIGN FOR A BALANCING TOY

Dominic M. Desiderio, McKees Rocks, Pa.

Application April 15, 1947, Serial No. 138,407

Term of patent 7 years

(Cl. D34—15)

To all whom it may concern:

Be it known that I, Dominic M. Desiderio, a citizen of the United States, residing in McKees Rocks, county of Allegheny, and State of Pennsylvania, have invented a new, original, and ornamental Design for a Balancing Toy, of which the following is a specification, reference being had to the accompanying drawing, forming part thereof.

Fig. 1 is a top plan view of a balancing toy showing my new design,

Fig. 2 is a front view thereof, and

Fig. 3 is a fragmentary side view of the balancing toy.

I claim:

The ornamental design for a balancing toy, as shown.

DOMINIC M. DESIDERIO.
